UNITED STATES PATENT OFFICE.

FRANKLIN P. TOOF, OF PADUCAH, KENTUCKY, AND CHARLES E. LANCASTER, OF WASHINGTON, DISTRICT OF COLUMBIA; SAID LANCASTER ASSIGNOR TO SAID TOOF.

MOP.

1,371,988.

Specification of Letters Patent. Patented Mar. 15, 1921.

Application filed December 21, 1917. Serial No. 208,265.

To all whom it may concern:

Be it known that we, FRANKLIN P. Toof and CHARLES E. LANCASTER, citizens of the United States, and residents, respectively, 5 of Paducah, in the county of McCracken, in the State of Kentucky, and of Washington, in the District of Columbia, have invented new and useful Improvements in Mops, of which the following is a specification.

10 The present invention relates to mops, and has particular reference to certain improvements in the mop structure set forth and claimed in the application for Letters Patent of the United States filed April 17, 1916, 15 by Franklin P. Toof, and bearing Serial Number 91,769.

As disclosed in the above identified application, and as actually reduced to practice, the swatches of mops are each made up of 20 innumerable fiber, such as spun cotton, secured to a sheath of flexible material, which may be cloth, the fiber secured between the plies of the sheath with stitching securely holding the fiber in place and providing a 25 swatch structure which is both flexible and durable. To shape and support this type of swatch for use, a frame of wire or stamped metal is usually employed, and is usually polygonal in shape including spaced end 30 portions on which the sheath of the swatch may be easily threaded, the sheath concealing the gap between the spaced end portions of the frame.

Frames of this general character are of 35 open construction and the fibers of the swatch are to a large extent forced up into the open frame when the mop is applied to a surface particularly against walls and ceilings, and also when pressure is brought 40 upon the mop frame. Under these conditions, the maximum amount of fiber is not brought into operation and consequently the full efficiency of the mop is not obtained.

It is therefore an object of the present invention to provide an improved mop frame of such construction as to detachably hold the swatch in place and to hold the fibers from turning up into the frame; a frame which embodies simplicity, lightness in 50 weight, and durability in construction; and a frame which may be readily stamped economically from sheet metal.

Another object of this invention is to provide a mop frame adapted to detachably re-

ceive the swatch and hold the ends thereof 55 at an angle to prevent the accidental slipping of the swatch from the frame when the mop is in use; the ends of the swatch being preferably turned inward toward each other at the end of the frame to offer resistance to 60 withdrawal from the frame except when pressure is applied to the inturned ends of the swatch.

The above, and various other objects and advantages of this invention will be in part 65 described, and in part understood, from the following detailed description of the present preferred embodiment, the same being illustrated in the accompanying drawings, 70 wherein—

Figure 1 is a perspective view of a mop constructed according to this invention.

Fig. 2 is a perspective view of the swatch frame, the parts being removed therefrom.

Fig. 3 is a top plan view thereof with the 75 handle connecting bolt applied thereto.

Fig. 4 is a transverse section through the frame taken substantially on the plane indicated by the line 4—4 in Fig. 3, and showing a swatch applied thereto.

Fig. 5 is a fragmentary plan view of a sheet metal blank stamped to form a number of mop frames cut therein and prior to being separated and bent into shape.

Fig. 6 is a top plan view of a slightly 85 modified form of the mop frame.

Referring to these drawings, a swatch is disclosed of the construction specifically set forth in the copending application above referred to, and which broadly comprises a 90 sheath A open at opposite ends and having stitched thereto a number of cotton or the like fibers B for contact with the surface to be cleaned or polished.

The improvement of this invention is directed to the structure of the frame, which in the present instance comprises a body plate 10 of triangular or other suitable form to provide a closed body part. The plate 10 has at its inner end, or at its broader end, 100 a rearwardly projecting neck 11 from which laterally extend bars 12, the latter being held in spaced relation from the plate 10 by the neck 11. The bars 12 are of angular formation, the same extending laterally from the 105 neck 11 and thence longitudinally in spaced relation to the lateral edges of the body plate and terminating in closely spaced apart re-

lation at the forward end or apex of the body plate. Preferably, the lateral portions 13 of the bars are bent up in position with their transverse longitudinal planes at right angles to the planes of the rear lateral extensions of the bars 12, the bends in the bars being formed at their angled portions.

- The inner ends of the bars 12, which merge into the neck 11, are formed at preferably 10 an angle to provide shoulders 14 which are arranged at the rear edge of the frame, the said inner ends of the bars extending rearwardly and diverging from one another to form the shoulders. Stamped and struck 15 up from the body plate 10 of the frame, and intermediate the front and rear ends thereof, is a pair of laterally spaced apart and registering ears 15 adapted to support a detachable bolt or pivot pin 16.
- 20 The mop is provided with a handle C detachably secured to the frame, preferably by means of the coupling D specifically set forth in the above referred to application and comprising a preferably threaded socket 25 into which the end of the handle is detachably engaged and a cylindrical or sleeve portion E through which the bolt or pin 16 is adapted to pass. The handle C is thus pivotally connected to an intermediate portion 30 of the frame, and the frame is filled in by means of the body plate 10.

- When the frames are constructed from sheet metal as above described, they may be stamped or cut from a blank or strip of 35 sheet metal 17 with the apices of the frames alternately arranged at the opposite lateral edges of the strip 17 to economize in the consumption of material and also to admit of rapidity in the process of manufacture.
- 40 As shown in the blank illustrated in Fig. 5, the lateral portions 13 of the bars 12 are flat and lie in the plane of the blank, and are adapted to be bent up into the form shown in the other views of the drawings 45 subsequent to the cutting or stamping operation.

As shown in Fig. 6 the neck portion is formed by the independent returned and curved ends 18 of the arms 12, the ends 18 50 preferably extending into the rear end of the body plate 10 and formed by curved relatively deep recesses or slots 19 formed in the rear edge of the plate 10 to separate the bars from the plate. These returned ends 55 18 of the bars provide between them a relatively deep recess or concavity in the rear end of the frame.

By bending the lateral portions 13 of the bars upwardly to lie in vertical planes, the 60 lower edge portions of the bars 13 are disposed above the horizontal plane of the body plate 10 so that when the sheath A of the swatch is threaded over the bars, the sheath is held substantially above the plate A and 65 the fibers are free to spread against the under

side of the plate and are supported from turning up between the bars. The bars 12 are of sufficient width to sustain the pressure placed upon the frame without bending the bars, and the lateral portions 13 thereof are 70 turned up into an edgewise position to further strengthen the bars as well as to hold the sheath in raised position.

In use, when it is desired to attach the swatch to the frame, it is only necessary to 75 thread the opposite open ends of the sheath A over the forward ends of the arms 13 introducing the sheath through the gap between the arms 13. The sheath A is slid back upon the arms 13, and over the bends 80 thereof to the inner ends of the bars 12. The free ends of the sheath A engage about the shoulders 14 and the sheath is thus frictionally held to the bars from sliding forwardly. As shown in Fig. 6 the curved inner ends of the bars may be employed for returning the free ends of the sheath in a direction toward the forward end of the frame and thus further insure the retension of the sheath A in taut position upon the 85 bars.

When a sheath is thus positioned the fibers B extend below the frame and when spread and placed under pressure are supported against the surface to be cleansed by the 90 body plate 10 which extends across the frame and substantially fills the space between the lateral arms 13 of the frame bars. The slots formed between the marginal edges of the plate 10 and the bars 12 is sufficient to receive the sheath when placed over the bars and admit of the manipulation of the sheath in positioning and removing it. 100

The forward spaced apart ends of the arms 13 are preferably rounded to admit 105 the easy introduction of the ends of the sheath A thereover, and the intermediate portion of the sheath is adapted to close the gap between the arms when the sheath is drawn taut over the same.

The above specifically described mop frame is but one form which may be used, and it is to be understood that various changes and modifications may be made in this form to construct the same from sheet 115 metal or otherwise, without departing from the spirit of this invention, the changes and modifications being restricted only by the scope of the following claims.

What is claimed is:

1. In a mop, the combination with a handle, a frame pivotally carried by the handle, and a swatch including a sheath, side bars carried by the frame and extending longitudinally at opposite sides thereof and 125 spaced apart at their forward ends to receive the sheath thereover, said frame having an intermediate filler portion for maintaining the swatch beneath the frame.
2. In a mop, the combination with a han- 130

dle, and a swatch including a sheath, of a frame having an intermediate portion pivoted to the handle and provided with a flat under side and laterally disposed arms 5 spaced from the intermediate portion and terminating in spaced relation at their ends to receive said sheath thereover, said intermediate portion of the frame being adapted to hold the swatch at the under side of the 10 frame.

3. In a mop, the combination with a swatch having a sheath, of a frame comprising a flat plate with opposite extending bars branching from the rear end of the plate 15 and extending forwardly in spaced relation from and around the rear corners of the plate, said bars being spaced apart at their forward ends to form a gap for the reception of said sheath over the bars.

20 4. In a mop, the combination with a swatch having a sheath, of a frame comprising a body plate and arms diverging laterally from the plate at the rear end thereof

and being curved forwardly about the rear corners of the plate and adapted to receive 25 said sheath rearwardly thereover, the forwardly extending ends of the arms being spaced above the horizontal plane of the plate to hold the sheath above the latter and engage the fiber of the swatch against 30 the under side of the plate.

5. A mop frame including a plate of substantially triangular shape, arms carried by the central portion of one side of the plate and extending in spaced relation around the 35 two adjacent sides of the triangular plate and having the ends of the arms terminating in proximity to the corner of the plate formed by said adjacent sides, said arms adapted to slidably receive the sheath of a 40 swatch, the plate adjacent the portion to which said arms are connected, being provided with recesses.

FRANKLIN P. TOOF.
CHARLES E. LANCASTER.
